CLAIM

The ornamental design for a keyless lock, as shown and described.

DESCRIPTION

FIG. 1 is a top, front, and right side perspective view of a keyless lock showing our new design;

FIG. 2 is a front elevation view thereof;

FIG. 3 is a top plan view thereof;

FIG. 4 is a bottom plan view thereof;

FIG. 5 is a left side elevation view thereof;

FIG. 6 is a rear elevation view thereof;

FIG. 7 is a right side elevational view thereof;

FIG. 8 is a left side elevational view thereof, with the protective cover shown rotated to an open position, the right side being a mirror image of that shown; and

FIG. 9 is a front elevational view thereof, with the protective cover shown rotated to an open position.
